(57) **CLAIM**

The ornamental design for a beverage dispensing container, as shown and described.

DESCRIPTION

FIG. 1 is a perspective view of our new beverage dispensing container, which includes a partially or fully removable access opening on the top panel and a partially or fully removable pour spout opening on the front panel.

FIG. 2 is a front elevation of the beverage dispensing container.

FIG. 3 is a rear elevation of the beverage dispensing container.

FIG. 4 is a right side elevation of the beverage dispensing container.

FIG. 5 is a left side elevation of the beverage dispensing container.

FIG. 6 is a top plan view of the beverage dispensing container;

FIG. 7 is a bottom plan view of the beverage dispensing container; and,

FIG. 8 is another perspective view of the beverage dispensing container with the access opening folded downward and the pour spout opening partially removed.

The broken lines shown in FIGS. 1, 2, 6 and 8 indicate lines of weakness at which the material of the beverage dispensing container can be separated and/or folded and form part of the claimed design.

The broken lines within the pour spout opening in FIG. 8 represent unclaimed parts of the design.
